UNITED STATES PATENT OFFICE

169,447

WINDOW SCREEN DEFLECTOR

Felix Labrise, New York, N. Y.

Application November 12, 1952, Serial No. 22,240

Term of patent 3½ years

(Cl. D21—6)

To all whom it may concern:

Be it known that I, Felix Labrise, a citizen of the United States, residing in the county of the Bronx, city and State of New York, have invented a new, original, and ornamental Design for a Window Screen Deflector, of which the following is a specification, reference being had to the accompanying drawings, forming a part thereof.

Fig. 1 is a perspective view of a window screen deflector embodying my new design; and

Fig. 2 is a rear perspective view thereof.

I claim:

The ornamental design for a window screen deflector, as shown.

FELIX LABRISE.
